UNITED STATES PATENT OFFICE.

LEVI D. YORK, OF PORTSMOUTH, OHIO.

BLAST-FURNACE FOR BURNING GASEOUS FUEL.

SPECIFICATION forming part of Letters Patent No. 288,607, dated November 13, 1883.

Application filed February 12, 1883. (No model.)

To all whom it may concern:

Be it known that I, LEVI D. YORK, of Portsmouth, Scioto county, in the State of Ohio, have invented certain new and useful Improvements Relating to Blast-Furnaces, of which the following is a specification.

I work the furnace by forcing in at the bottom air and gas, both at a high temperature. I can use solid fuel in a less proportion than usual, or I can dispense with it entirely, and produce the heat from the combustion alone of the gas thus forced in.

The following is a description of what I consider the best means of carrying out the invention.

The accompanying drawings form a part of this specification.

Figure 1 is a vertical section, some of the parts being in elevation. Fig. 2 is an outline, showing a different arrangement of the parts. This involves a somewhat different mode of working.

Similar letters of reference indicate corresponding parts in both figures.

Referring to Fig. 1, A is a blast-furnace, which may be of ordinary dimensions, form, and proportions.

B is an air-heating stove, performing the usual functions of such device by absorbing heat from the products of combustion escaping from the blast-furnace through the pipes b, and imparting it to fresh air forced by the blowing means C through the pipe c, and thence through tuyeres c' into the furnace A at several points near the base. The blower C is driven by an engine or other power. (Not represented.)

It will of course be understood that pipes c and d continue from the blowers to the tuyeres c' and fire-box E, and that the portions within the stoves B F are adapted to be bathed by the heated gases which enter into the stoves through the pipes b, the said gases thence passing to the outer air through passages. (Shown in dotted lines.)

The gas-producing furnace E is kept filled with bituminous coal or other suitable solid fuel, in lumps of proper size to allow the air a tolerably free passage through its interstices.

D is a blowing apparatus, which is worked by an engine or engines. (Not represented.) This blower D forces the air through a pipe, d, and

heating stove F into the base of the gas-producing furnace E.

The fuel in the furnace E is maintained at such depth that the gases rising therefrom are largely carbonic oxide and hydrocarbon gas adapted to produce a high degree of heat by the combustion of the gaseous mixture in the blast-furnace. The action going on in the blast-furnace is of the usual character, except that the proportion of solid fuel to the ore and flux being reduced, the zone of preparation is diminished, and may be done away with altogether when sufficient gas is used to supply heat, requiring only ore and flux to be put into the blast-furnace at the top.

My furnace is more efficient than ordinary blast-furnaces, for reasons long recognized in various forms of low furnaces. A given size of furnace is more efficient and the fuel is economized. The quantity of combustible gas and air is controlled by working the blowers C and D at varying rates, or by the employment of any suitable valves, as indicated, or by both these means.

In the form of apparatus shown in Fig. 2, instead of forcing the air before it is supplied to the gas-furnace, the blowing apparatus is placed intermediate between the gas-producing furnace and the blast-furnace.

It will be understood that the gas is considerably lowered in temperature, either by radiation from the pipes, or by its passage through one or more pipes specially cooled by means not represented, so that it reaches the blowing means at a temperature that allows it to be worked. I propose to determine by experiment what is the highest temperature at which gas can be pumped or otherwise forced, and take care to never have the gas exceed that temperature. This form of the apparatus gives the advantage that the gas-producing furnace is relieved from pressure.

It will be understood that in case the furnace is worked under pressure, as in Fig. 1, means are provided, as by an air-lock with duplicate valves, for introducing the successive charges of fuel without allowing the gas to blow out.

Fig. 1 shows only one chamber of the gas-producing furnace. Fig. 2 shows two, and it will be understood that there may be four, eight, or any other desired number of chambers.

It will also be understood that the blast-furnace itself and its several auxiliaries may be varied in proportions and in arrangement.

I have omitted much detail in the drawings.

- 5 Each of the parts may be made in any ordinary or suitable manner, and with all the necessary attachments. It is essential only that a liberal supply of combustible gas be obtained from a gas-producing furnace, E, and be driven into the base of the blast-furnace A, and that a sufficient quantity of fresh air be properly presented thereto in the blast-furnace, and that both be supplied hot.

The main pipes may be placed under ground or over head. The gas and air may be passed into the furnace at the same level. In such case the tuyeres for the two may have their openings of proper dimensions arranged at an angle, so as to cause the jet from one gas-tuyere to impinge upon the jet from an adjacent air-tuyere. I can use any desired number of tuyeres.

Any ordinary or suitable form of air-heating stoves may be used for the stoves B and F.

I have represented in Fig. 2 but one blower, D, and but one heating-stove, F; but it will be understood that there are corresponding blowing means and heating-stove to supply the hot air. I have not deemed it necessary to show in Fig. 2 the air-supplying apparatus further than the pipe through which the heated air is received.

I claim as my invention—

In combination with the blast-furnace A and air-heating stove B, and its connections for driving heated air into A, the gas-producing source and stove F, and their connections for driving the gas at a high temperature into A, as herein specified.

In testimony whereof I have hereunto set my hand, at Portsmouth, Ohio, this 1st day of February, 1883, in the presence of two subscribing witnesses.

LEVI D. YORK.
